UNITED STATES PATENT OFFICE.

PHILIP J. HANDEL, OF MERIDEN, CONNECTICUT.

KILN.

SPECIFICATION forming part of Letters Patent No. 481,562, dated August 30, 1892.

Application filed November 18, 1891. Serial No. 412,277. (No model.)

To all whom it may concern:

Be it known that I, PHILIP J. HANDEL, a citizen of the United States, residing at Meriden, in the county of New Haven and State of Connecticut, have invented certain new and useful Improvements in Kilns; and I do declare the following to be a full, clear, and exact description of the invention, such as will enable others skilled in the art to which it applies to make and use the same, reference being had to the accompanying drawings, and to the letters of reference marked thereon, which form a part of this specification, and represent, in—

15 Figure 1, a side view of a device well calculated to illustrate the spirit of my invention. Fig. 2 is a back view of the same device, both views being shown in section for the purpose of better illustration.

20 In Fig. 1, A represents a heating-chamber, and B B are vertical flues passing through the same.

C is the fire-box, and D is the escape-flue for the heated air and gases.

25 a a a a are sprocket-wheels mounted upon the shafts b b b b.

c c represent endless chains, which pass over the sprocket-wheels, said chains being provided with hooks for the purpose of attaching frames or other devices for supporting the work that is to be passed through the flues of the kiln. As will be seen, the chains are calculated to pass through the flues from the top downward. Any well-known means may 35 be employed to operate the chains—such as a crank attached to one of the shafts—and any suitable mechanism may be employed to stop and hold the work in the desired position. It is obvious that the flues may be of any desired shape or form, as square, round &c. I 40 wish it also understood that more than one fire-box may be employed, if found desirable.

As will be seen by reference to the drawings, two chains are caused to operate in each 45 flue, one on either side, as it affords a better means for attaching the work to be operated upon; but I would not have it understood that I limit myself to this way only, as it is obvious that a variety of ways may be employed 50 with equally good results. The vertical flues

pass through the heating-chamber and extend a sufficient distance above and below to accomplish the desired results.

The object of this invention is to produce a kiln in which different portions shall be subjected to and maintain different degrees of heat, and is designed more particularly for use in decorating glassware; but, as will readily be seen, is equally applicable to many other purposes, such as japanning, baking 55 pottery, &c.

The operation of the device is as follows: The work to be treated is introduced at the top of the flue by being attached to the chains and then lowered into the first section of the 65 same or the portion which extends above the heating-chamber. As this portion of the flue is open to the atmosphere, it is obvious that it will contain a lower degree of heat than the portion which extends through the chamber 70 below. In the first portion of the flue the work becomes gradually heated to a sufficiently-high temperature to be introduced into the baking portion or section, which passes through the chamber, when it is lowered into 75 this section, where it remains until it acquires the required amount of heat, when it is lowered into the annealing section or portion below the chamber, which, like the introduction-section, is open to the atmosphere, and 80 as the hot air from the heating-chamber rises the only heat which finds its way into the lower section is that which is carried in by the heated work as it is lowered into this section of the flue, the bottom of which may be closed 85 to prevent the cold air from reaching the work until it is sufficiently cooled to prevent disastrous results when taken from the kiln. It will also readily be seen that as one lot of work is lowered from the flue another 90 may be introduced into the introduction-chamber, and thus the work go on continuously. It will readily be seen that a number of flues may be operated at the same time, or by inserting dampers or partitions in the heating-chamber that one of them may be used independent of the rest; also, when found desirable, a damper or cover may be used to close 95 the top of the flue after the work is introduced.

Having thus described my invention, what I claim, and desire to secure by Letters Patent, is—

1. As an improvement in kilns, the combination, with a heating-chamber, of one or more vertical flues passing through said chamber and extended both above and below the same, for the purpose specified, said flues having no communication with the chamber, substantially as set forth.
2. As an improvement in kilns, the combination, with a heating-chamber, a fire box or boxes, and a stack communicating with the chamber, of one or more uninterrupted verti-

cal flues passing through the chamber and 15 extended above and below the same, forming a burning-passage, having its greatest temperature essentially at or near its center, and a continuous carrier adapted to pass entirely through said flue or flues, substantially as and 20 for the purpose set forth.

In testimony whereof I affix my signature in presence of two witnesses.

PHILIP J. HANDEL.
